UNITED STATES PATENT OFFICE.

EARL A. KNOWER, OF PACKWAUKEE, WISCONSIN.

PRIMING DEVICE.

1,217,015.

Specification of Letters Patent.

Patented Feb. 20, 1917.

Application filed June 9, 1916. Serial No. 102,735.

To all whom it may concern:

Be it known that I, EARL A. KNOWER, a citizen of the United States, residing at Packwaukee, in the county of Marquette and State of Wisconsin, have invented new and useful Improvements in Priming Devices, of which the following is a specification.

This invention relates to priming devices for multiple cylinder internal combustion engines such as are now commonly employed in automobiles, motor boats, aircraft and the like, the object in view being to provide a device of the character referred to which is immediately accessible to the driver without leaving his seat and by means of which all of the cylinders of the engine may be quickly and simultaneously primed for starting purposes, particularly in cold weather, the device being of such a character that it may be operated by simply pushing and pulling upon a handle located in rear of the dash of the machine.

With the above and other objects in view, the invention consists in the novel construction, combination and arrangement of parts, as herein described, illustrated and claimed.

In the accompanying drawings:—

Figure 1 is a vertical longitudinal section through a priming device embodying the present invention, showing the normal or non-priming position of the plunger.

Fig. 2 is a similar view showing the plunger in its priming position.

The priming device contemplated in this invention comprises, in the preferred embodiment thereof, a shell or casing which is of sufficient length to extend over the heads of all the cylinders of the engine so that it may be connected to the cylinders by means of tubular extensions or nipples 2 which occupy the positions now usually occupied by the priming cups.

The casing 1 is preferably square or rectangular in cross section and mounted therein is a plunger 3 which fits snugly within the casing 1 and corresponds in cross sectional shape thereto so as to prevent the plunger from turning within the casing, and thereby insuring the proper registration between the measuring chambers of the plunger and the connections 2 which lead to the cylinders of the engine. The plunger 3 is movable longitudinally within the casing 1 and is formed with a plurality of measuring chambers 4 extending there-

through from top to bottom, each of said chambers being so proportioned as to contain an amount of priming liquid sufficient for each combustion chamber of the engine. 60 The measuring chambers 4 extend entirely through the plunger 3 from top to bottom and in the position illustrated in Fig. 1, the upper extremities of the chambers 4 register with ports 5 in the bottom of a distributing chamber 6 which is located at the top of the casing 1 and which contains a supply of priming liquid delivered thereto by means of a feed pipe 7 leading from an elevated source of supply 8 such as a tank 70 which may either consist of the fuel tank of the car or an auxiliary tank provided specially for priming purposes.

The ports 5 are located out of line with the ports 9 with which the lower extremities 75 of the chambers 4 register so that when the plunger 3 is in the position shown in Fig. 1, the measuring chambers 4 are in line with the ports 4 and receive charges of priming liquid. When the plunger is moved to the 8 position shown in Fig. 2, the lower ends of the chambers 4 register with the ports 9 and the priming liquid then passes to the several cylinders of the engine. When the plunger 3 is returned to the position shown in 85 Fig. 1, all communication is cut off between the measuring chambers 4 and the connections 2 thereby rendering the device safe in use.

The means for operating the plunger 90 comprises a plunger rod 10 which is fastened at one end to the plunger 3 and which passes through a stuffing box 11 in one end of the casing 1. The plunger rod 10 passes through an opening in the dash where it is 95 provided with a suitable head or handle 12. The opposite portion of the casing 1 is extended sufficiently to form a compartment 13 divided from the main compartment by means of a partition wall 14 formed with 100 an opening 15 through which passes a guiding stem 16 at that end of and projecting from the plunger 3. A coiled expansion spring 17 surrounds the stem 16 and is located in the compartment 13, one end of 105 said spring bearing against a disk-shaped collar 18 fast on the stem 16. The spring 17 serves to return the plunger 3 to a position where communication is cut off with the connections 2 leading to the engine. 110 The partition wall 14 prevents leakage into the spring compartment 13.

In order to prime the engine, it is only necessary to push the handle 12 to the right in Fig. 1 thereby permitting the contents of the measuring chambers 4 to pass through the connections 2 to the engine. The handle 12 is then released whereupon the spring 17 serves to return the plunger to its initial position, cutting off all communication and feed of priming liquid to the engine cylinders.

I claim:

A priming device for multiple cylinder internal combustion engines, comprising a casing extending lengthwise of the battery of cylinders above the same and formed with outlet pipes in communication with the engine cylinders, said casing being also formed with a distributing passage extending longitudinally of the top of said casing

and having ports leading into said casing and out of vertical alinement with the outlet pipes, said distributing passage being in communication with a source of supply for the priming agent, a plunger movable longitudinally within said casing provided with a stem and formed with a plurality of measuring chambers adapted to move into and out of registry with the said ports and also into and out of registry with the said pipes, means for operating said plunger including a spring, and a partition in said casing having a guide opening for the plunger stem and forming a separate spring housing compartment.

In testimony whereof I affix my signature.

EARL A. KNOWER.

Copies of this patent may be obtained for five cents each, by addressing the "Commissioner of Patents, Washington, D. C."
